UNITED STATES PATENT OFFICE.

GEORGE ALBEN E. LUNDELL, OF CHICAGO, ILLINOIS, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 20, 1919. Serial No. 346,351.

To all whom it may concern:

Be it known that I, GEORGE ALBEN E. LUNDELL, a citizen of the United States, residing at Chicago, in the county of Cook 5 and State of Illinois, have invented certain new and useful Improvements in Telephone-Exchange Systems, of which the following is a specification.

This invention relates to automatic telephone exchanges, and more particularly to full automatic telephone exchanges in which senders are employed for registering the numerical designation of the called line and for controlling the setting up of the connection.

In such automatic exchanges registers are set into position by the manipulation by the calling subscriber of a calling device or dial. The operative circuit of such calling device 20 includes the line wires connecting the substation with the central office, and a control relay and source of energy at the central office, and over this circuit impulses of current are transmitted.

The correct operation of the central office selecting mechanism depends upon the proper operation of this circuit. Hitherto, it has been found that when the calling subscriber is one of the parties on a poly-station line, that is a line having a plurality of substations and having only a single pair of wires extending from such stations to the central office, the operation of the pulse circuit is rendered unreliable by the shunting effects of the condensers at the other stations of the line.

It is the object of the present invention to provide a simple and efficient pulse circuit for such poly-station lines, whereby the accuracy and reliability of the registering operation is improved.

Another object of the present invention provides for the use of a slow release relay for controlling the shifting operation where- 45 by one register after the other may be rendered active in connection with the pulse circuit. According to this feature a contact of such slow relay in combination with the register switches, initiates the sending 50 operation and controls the restoration of the register switches. A simple form of register control switch is thereby obtained.

A further object relates to an improved selection of the ringing current for poly- 55 station lines, whereby a single set of termi-

nals may be used for all of the stations of the selected line, only one set of impulses being required for selection of both the line and the ringing current.

It is understood that the disclosure herein 60 set forth is only one of a variety of expressions which the invention is capable of receiving, and that the scope of the invention is not to be determined by it, reference being had to the appended claims for that purpose. 65

The invention will be understood more in detail by reference to the accompanying drawings, wherein is disclosed so much of a telephone system as is necessary to a full understanding of the invention. Figs. 1 70 and 2 taken collectively represent a connection from a calling to a called subscriber. Fig. 1 represents a first selector and control apparatus therefor, a sender including the counting relays, a plurality of register 75 switches, a register control switch and controlling relays therefor; and shows a party line having four stations. Fig. 2, which is to be placed immediately to the right of Fig. 1 represents a second switch of the 80 train, extending from a calling subscriber to a called subscriber, and includes selective ringing apparatus for signalling the individual stations of a poly station line. Fig. 2 also includes a portion of the counting 85 relays of the sender 119.

In Fig. 1 the subscriber's station 101 comprises the calling device 102, the purpose of which is to produce operating impulses by interrupting the circuit at the substation. 90 Stations 100, 101, 103, 104, are severally connected to the line wires 105, 106. Such stations are provided with ringers 107, 108, 110, and 111, each of which is normally in series with a condenser such as 112.

The conductors 105, 106 of the calling line may be extended to the first selector by means of a line finder or equivalent, upon the removal of the receiver at the calling station. Such first selector may be of any 100 suitable type, that shown in the drawings being a so-called panel selector in which the terminals are arranged in vertical rows, and in which the wipers are adapted to travel in a vertical direction. Sequence 105 switches 131, 154, and 213 comprise sets of springs such as that shown at 191, adapted to close contacts in the various positions of the sequence switch. The numerals which appear adjacent to the sequence switch con- 110

acts diagrammatically represented in various parts of the drawings, indicate the positions of the sequence switch at which these contacts are closed, with the exception that the centering springs, one of which appears immediately above the power magnet of each of the sequence switches, are open only at the positions indicated by the numeral adjacent thereto, and therefore the sequence switches can stop only in these positions. Motor mechanism is provided for rotating the sequence switch through its successive positions. This mechanism is set into operation during the energization of the power magnet in the sequence switch.

Sequence switch contacts 125 and 124 of the sequence switch 131, associated with the first selector switch, are adapted in position 1 of this sequence switch to extend conductors 106 and 105 to conductors 123 and 126, which in turn may be extended to the sender circuit 119 by means of a line finder, or equivalent means. The sender includes the sequence switch 154, the counting relay designated 0, 0', 1, 1', etc., as well as a plurality of register switches, and a register control switch therefor. In the system of the present disclosure two register switches are shown, the first controlled by the magnet 138, which upon energization of its magnet and attraction of its left hand armature causes the pawl 140 to step the ratchet wheel 141 and the wipers 120, 130, 142, and 143, in a clockwise direction. The ratchet wheel 141 and the wipers 120, 130, 142, and 143, are thus stepped in a step by step movement one step for each movement of the pawl 140. The retraction of the armature of magnet 138 withdraws the pawl 140 from a tooth of the ratchet wheel 141 and places it in position for again advancing the ratchet wheel 141 upon subsequent operation of the magnet 138. Similarly magnet 148 controls the movement of the ratchet wheel 151 and the wipers 122, 127, 152, and 153, said magnet, ratchet wheel, and wipers being parts of the second register switch adapted to register the second digit of the numerical designation of the called subscriber's number. The register control switch comprises the stepping magnet 144 with its ratchet wheel 146 and the wipers 145 and 136. The energization of the magnet 144 attracts the armature 191 and moves the pawl 192 into engagement with the next tooth of ratchet wheel 146. Upon deenergization of magnet 144 and the retraction of armature 191 pawl 192 forces the ratchet wheel 146 and the wipers 136 and 145 one step in a counter clockwise direction. Each of the wipers 120, 130, 142, 143, 122, 127, 152, 153, 136, and 145 is provided with a row of terminals with which it makes contact and upon being stepped away from the last terminal of the row is brought again into engagement with the first or normal terminal. Selector 220 of Fig. 2 is of the so-called panel type, and is provided with wipers 223, 224, and 225, adapted to move in an upper direction over the terminal bank 226, and with commutator brush 214 which passes over the conducting segments such as 215, 228, and 231, of the commutator plate 227. A source of ring current 232 produces a plurality of variously characterized currents and the ringers 107, 108, 110, and 111 of the calling line and 233, 234, 235, and 236 of a called line are adjusted to operate upon currents from such source 232. A connecting board 237 is provided by means of which the different kinds of current from the source 232 may be employed at will.

The line wires 105, 106, extend from substations 100, 101, 103, and 104, to the central office 116, and may be connected in a well known manner to the sender 119 at such central office. When the subscriber at station 101 desires to originate a call for a subscriber such as 201, he removes his receiver from the switch hook. A circuit is closed from grounded battery 117, pulse relay 118, register switch wiper 120, conductor 121, register switch wiper 122, conductor 123, sequence switch contact 124, conductor 106, substation equipment 101; interrupter 102, conductor 105, sequence switch contact 125, conductor 126, register switch wiper 127, conductor 128, register switch wiper 130 to ground.

The operation of relay 118 closes a local circuit from grounded battery 132, winding of slow release relay 133, conductor 134, front contact of relay 118 to ground, operating the relay 133.

The subscriber at station 101 now manipulates the calling device or interrupter 102 in accordance with the first digit of the called subscriber's number. For the purpose of illustrating we will assume that the calling device interrupts the circuit three times.

The release of relay 118 upon the first opening of interrupter 102, causes the closure of the following circuit, ground, armature and back contact of relay 118, front contact of relay 133, winding of relay 135, register control switch wiper 136, conductor 137, register switch magnet 138 to grounded battery. The energization of magnet 138 attracts its armature which by means of the pawl 140 causes the movement of the ratchet wheel 141 and the wipers 120, 130, 142, 143, one step in a clockwise direction. The opening of the contact 102 has left a charge from the battery 117 on the condensers 113, 114, 115. The movement of the wipers 120, 130, from the first point to the second point of their arcs causes a flow of current from grounded battery 130

117 through winding of relay 118 to the conductor 128 in turn through wiper 127, conductor 126, sequence switch contact 125 to the conductor 105, thus to the side of the 5 condensers 113, 114, 115, opposite that to which this grounded battery was previously connected. Similarly the ground connection by way of wiper 130 is shifted to the conductor 121, wiper 122, conductor 123, 10 sequence switch contact 124, conductor 106 to the side of the condensers 113, 114, 115, opposite to that to which this ground was previously connected. Thus it will be seen 15 that a source of current flows through the winding of relay 118, as a result of the previous charge left on the condensers 113, 114, 115, being discharged through the path described, and furthermore as a result of a new charge in the opposite direction to 20 such condensers. Contact 102 of the calling device now closes and reestablishes a circuit for relay 118 as follows: grounded battery 117, winding of relay 118, wiper 120, conductor 128, wiper 127, conductor 126, sequence switch contact 125, conductor 25 105, interrupter contact 102, substation equipment 101, conductor 106, sequence switch contact 124, conductor 123, wiper 132, conductor 121, wiper 130 to ground. 30 The operation of relay 118 has been materially assisted and quickened by the surge of current through the condensers. A second opening of interrupter contact 102 again deenergizes the relay 118 and causes 35 the operation of magnet 138 a second time. The consequent operation of the magnet 138 again moves the ratchet wheel 141 and the wipers 120, 130, 142, and 143, to the third point, and a connection is thus established 40 from grounded battery 117 over which the condensers 113, 114, 115, discharge through the relay 118, and take up a new charge in the opposite direction, so that the surge of current through the winding of relay 118 45 assists the operation of this relay as previously described. Thus it will be seen that the operation of the register magnet 138 and the movement of wiper arms 120 and 130 alternately charges and discharges 50 the condensers 113, 114, and 115, the charge and discharge path including windings of the relay 118 and consequently aiding the operation of this relay. Upon each release of the armature of the relay 118 a 55 circuit is closed through the winding of slow release relay 135 as described above. The relay 135 is slow acting and remains energized during the vibration of the armature of relay 118. Relay 135 closes also a 60 circuit for magnet 144 from ground, armature and front contact of relay 135, winding of magnet 144 to grounded battery 117. Magnet 144 controls upon its deenergization the stepping of the register control 65 switch ratchet 146 and wipers 136 and 145. After the calling subscriber sends out the first series of impulses the contact 102 remains closed, and the relay 118 remains operated, for a sufficiently long period to allow the deenergization of slow acting relay 135, which in turn opens the circuit of the magnet 144. The deenergization of magnet 144 results in the movement of ratchet wheel 146 and wipers 136 and 145 one step in a counter clockwise direction. 70

The calling subscriber now proceeds to send out the second set of operative impulses causing the intermittent operation of the relay 118 for each opening of the interrupter contact 102, relay 118 releases once 80 and closes once the following circuit: grounded battery 147, second register switch magnet 148, conductor 150, register control switch wiper 136, now in its second position, winding of slow release relay 135, 85 front contact of relay 133, back contact and armature of relay 118 to ground. Register switch ratchet wheel 151 and its wipers 122, 127, 152, and 153, are thus caused to step one step in a clockwise direction for 90 each opening of contact 102. Wipers 122 and 127 during such movement of second register switch reverses the connections to the line wires 105, 106, in a manner similar to wipers 120 and 130 of the first register 95 switch, and causes, as previously described, a discharging and charging surge for the relay 118 in the above described manner; and upon the cessation of the second set of impulses slow relay 135 is released, and 100 magnet 144 is deenergized, thus moving the ratchet wheel 146 and the wipers 136 and 145 one step in a counter clockwise direction. 105

As soon as the first set of impulses was sent in and the slow release relay 135 was deenergized, a starting circuit for initiating the movement of the sender sequence switch 154 is closed from grounded battery, power magnet of sequence switch 154, upper contact of sequence switch spring 155, conductor 156, wiper 153, conductor 157, wiper 143, conductor 158, back contact of relay 135 to ground, and under control of centering cam 160 sequence switch 154 is moved from its first to its second position. The sender sequence switch 154 now controls the selecting operation in the following manner. Upon reaching position 2 the sequence switch contact 161 closes the following circuit: grounded battery, winding of relay 162, lower right contact of sequence switch spring 163, conductor 164, winding of stepping relay 165, sequence switch contact 161, left hand back contact of the 0' counting relay, conductor 166, lower contact of sequence switch spring 167 to ground, energizing relays 162 and 165. Relay 162 closes at its left hand front contact by way of conductor 168, and lower left contact of sequence switch spring 163, a locking circuit 110

115

120

125

130

for itself independent of the lower right contact of sequence switch spring 163. The operation of relay 162 also closes a driving circuit for sequence switch 131, said circuit 5 including the power magnet sequence switch 131, upper left contact of sequence switch 170, right hand front contact of relay 162, to ground, causing the movement of sequence switch 131 out of position 1 into 10 position 2. When sequence switch 131 leaves position 1, the original circuit of relay 162 is opened at the lower right contact of sequence switch spring 163, but this relay is maintained energized over the locking 15 circuit described.

The operation of relay 165 in the circuit described above causes the number 3 counting relay to be operated in the following circuit: grounded battery, winding of counting relay 3, back contact and armature of counting relay 3', conductor 3, wiper 142, which is in its fourth position, lower contact of sequence switch spring 171, front contact and armature of relay 165 to ground. 20 Counting relay 3 becomes energized and closes for itself the locking circuit by way of sequence switch contact 172, armature and front contact of counting relay 3, winding of counting relay 3', winding of counting relay 3 to grounded battery, independent of the previously described circuit through the wiper 142, and the contact of relay 165. Although the winding of counting relay 3' is included in such locking circuit, this relay does not become energized 25 due to a short circuit around said winding by way of wiper 142, and the contact of relay 165. A circuit is now closed from a grounded battery through the winding of a driving magnet 173, sequence switch contact 174, right front contact of relay 162 to ground. The magnet 173 by attracting its armature 175 forces a brush rod 176 against a roller 177 constantly driven in the direction indicated by the arrow. Under the 30 control of this roller the brush rod 176 and with wipers 178, 180, and 181, and the commutator brush 182 mounted thereon is moved in an upward direction. Wipers 35 178, 180 and 181 are adapted to wipe over the contacts of terminal bank 183, and brush 182 is adapted to travel over the conducting and insulated segments 184 and 185 of a commutator plate 186.

When brush 182 reaches the first conducting plate 184 it connects ground through a conductor 187 and the upper contact of sequence switch spring 163, causing 40 thus the short circuiting of stepping relay 165. Upon its deenergization stepping relay 165 removes the short circuit from around the winding of counting relay 3', and this relay becomes energized. Counting relay 3' connects the conductor 3 through 45 its armature, and front contact, and the ar-

mature and back contact of counting relay 2' to counting relay 2, which then operates in the same manner as counting relay 3, to close a locking circuit for itself, and for the counting relay 2', when brush 182 reaches the next conducting segment 184. Thus when said brush 182 reaches the insulated segment 185, the short circuit is removed from the stepping relay 165, and this relay permits the operation of counting relay 2'. The operation of the counting relays continues in the same manner as described in connection with counting relays 2 and 3, until the counting relay 0' becomes energized. This circuit opens at its left 50 hand armature, and back contact, the circuit of relay 165, thus preventing the reenergization of stepping relay 165. The circuit of relay 162 is opened when brush 182 encounters the next insulating segment. 55

Relay 162 closes a circuit from grounded battery power magnet of sequence switch 131, lower left contact of sequence switch spring 170, right hand back contact and armature of relay 162 to ground, and for moving sequence switch 131 under control of centering spring 188 into its eighth position. The release of relay 162 opens the circuit of the driving magnet 173, causing the stopping of wipers 178, 180, and 181, in engagement with trunk conductors 202, 203, and 204. The testing of this trunk is accomplished in a well known manner in position 6 of the sequence switch 131, a circuit being closed from grounded battery through winding of the relay 205 of Fig. 2, test conductor 204, wiper 181, and sequence switch contact 190 to ground. Relay 205 becomes energized. The operation of the counting relay 0' closes a circuit from grounded battery power magnet of sequence switch 154, upper contact of sequence switch spring 191, inner armature and front contact of counting relay 0' to ground, for moving sequence switch 154 under control of its centering cam 160, out of position 2 and into position 3.

The release of the slow acting relay 135 after the second set of impulses has been transmitted, closes the following circuit: 115 ground, armature and back contact of relay 135, conductor 158, wiper 143, which is in an off normal position, conductor 157, wiper 153, which is in an off normal position, conductor 193, upper contact of sequence switch spring 194, power magnet of sequence switch 154 to grounded battery, for moving sequence switch 154 under the control of centering cam 160 out of position 120 3 and into position 4. During the movement of sequence switch 154 from position 2 to position 4, the locking circuit for the counting relays has been opened at sequence switch spring 172, and the operated counting relays are now released. 125 130

- A circuit is now closed from grounded battery 206 of Fig. 2, winding of relay 207, lower left contact of sequence switch spring 208, conductor 202, wiper 178, lower 5 contact of sequence switch spring 195, conductor 164, stepping relay 165, sequence switch contact 161, left hand back contact of the 0' counting relay, conductor 166, lower contact of sequence switch spring 196, wiper 180 conductor 203, lower contact of sequence switch spring 210 to ground, operating relays 207 and 165. Relay 207 becomes energized and closes at its right hand front contact a circuit by way of 10 conductor 211, and lower right contact of sequence switch spring 208, a locking circuit for itself independent of lower left contact of sequence switch spring 208. The operation of relay 165 in the circuit described above, causes the operation of the counting relay to whose conductor wiper 152 has been connected by the operation of the second register switch in the same manner as described for the number 3 counting 15 relay above. It will readily be understood that the wiper 152 and the counting relay conductor to which it is now connected has been determined by the number of impulses transmitted to register magnet 148, which 20 number in turn is dependent upon the designation of the called station. For the purpose of the present description it may be assumed that wiper 152 has been stepped three steps, and has been connected to conductor number 3. 25
- The operation of relay 207 has closed at its left hand front contact a circuit by way of lower left contact of sequence switch spring 212 for the power magnet of sequence switch 213, causing the movement of this sequence switch out of its first position. As soon as sequence switch 213 moves out of its first position the lower left contact of sequence switch spring 208 is broken, but 30 relay 207 is maintained energized independent thereof. As soon as sequence switch 213 reaches position 2 $\frac{1}{2}$ a short circuit from ground is closed through the upper right contact of sequence switch spring 208, whereby the stepping relay 165 is deenergized and the counting relay of the upper row is operated. The movement of sequence switch 213 under control of relay 207 continues until the upper right contact of sequence switch 208 has short circuited the stepping relay 165 a sufficient number of times to operate the 0' counting relay, whereupon relays 207 and 165 become released. 35
- The operation of the 0' counting relay closes a circuit by way of sequence switch spring 191 for moving sequence switch 154 out of position 4, and under control of the centering spring 160, this sequence switch moves into 16. The opening of sequence 40 switch contact 172 releases the operated counting relays. In position 16 of sequence switch 154 a circuit is closed from ground, armature and back contact of relay 135, conductor 158, wiper 143, which is in an off normal position, conductor 157, wiper 153, which is in an off normal position, conductor 193, lower contact of sequence switch spring 194, back contact and winding of the second register switch magnet 148, to 45 grounded battery. Under control of its back contact the magnet 148 is intermittently operated until the wipers are restored to the normal or first terminal whereupon the circuit through conductor 193 is broken, and the magnet 148 is deenergized. A circuit is then closed from ground, armature and back contact of the relay 135, conductor 158, wiper 143, which is in an off normal position, conductor 157, wiper 153, conductor 156, lower 50 contact of sequence switch spring 155, back contact and winding of register switch magnet 138 to grounded battery, and under control of its back contact the register switch magnet 138 is intermittently operated until 55 wipers 120, 130, 142, and 143, are returned to normal whereupon the circuit by way of conductor 157 is broken, and the magnet 138 is deenergized. A circuit is now established from ground, armature and back contact of relay 135, conductor 158, wiper 143, conductor 197, wiper 145, which is in an off normal position, back contact and winding of register control switch magnet 144 to 60 grounded battery 117. Under control of its back contact magnet 144 is intermittently operated, until the wipers 136 and 145 are returned to their normal or first position, whereupon the magnet 144 is deenergized. 65
- A circuit is now closed from ground, armature and back contact of relay 135, conductor 158, wiper 143, conductor 197, wiper 145, lower contact of sequence switch spring 191, power magnet of sequence switch 154 to 70 grounded battery, for moving sequence switch 154 out of position 16. Under control of its centering spring 160 sequence switch 154 moves into its first or normal position. The apparatus of sender 117, including the register control switch, the register, the counting relays, and the sequence switch 154 is now restored to normal and ready for use on a subsequent call. 75
- When the sequence switch 154 reaches position 10, a circuit is closed from ground, sequence switch spring 198, lower right contact of sequence switch spring 170, power magnet of sequence switch 131 to grounded battery, for moving sequence switch 131 out of position 8. Under control of its centering 80 spring 188 sequence switch 131 moves into its 16th position. Sequence switch springs 124 and 125 break the circuit by way of conductors 123 and 136 for relay 118 and this relay deenergizes causing in turn the release of 85 130

local relay 133. A circuit is now established from grounded battery 12, lower left winding of repeating coil 13, winding of relay 14, upper contact of sequence switch spring 124, 5 conductor 106, substation 101, interrupter contact 102, conductor 105, upper contact of sequence switch spring 125, upper left winding of repeating coil 13 to ground. Relay 14 is operated for a purpose which will subsequently be set forth.

Returning now to relay 207, which in the case considered released after sequence switch spring 208 applied the short circuit ground four times, since it required four 10 such closures to operate the 0' counting relay, consequently relay 207 is released when the sequence switch 213 reaches position 6. A circuit is then closed from ground, brush 214, conducting segment 215, upper 15 contact of sequence switch spring 216, conductor 217, driving magnet 218 of selector 220, to grounded battery. The magnet 218 by attracting its armature forces a brush rod 221 against constantly driven roller 222, 20 and the brush rod 221 with wipers 223, 224, 225, are moved in an upward direction over the contacts of terminal bank 226, and brush 214 is moved in an upward direction over the commutator plate 227. When brush 25 30 35 40 45 50 55 60 65 70 75 80 85 90 95 100 105 110 115 120 125 130 214 reaches conducting segment 228 a circuit is closed from ground, brush 214, segment 228, lower contact of sequence switch spring 230, conductor 217, driving magnet 218, to grounded battery, and the movement of brush rod 221 is continued. Similarly when the brush 214 contacts with such segments as 231 of the conductor plate 227, the circuit of driving magnet 218 is maintained. When the brush 214 passes off segment 232 and makes contact with segment 233 the driving magnet 218 is deenergized, and the wipers 223, 224, and 225 are stopped in contact with the terminals connected with conductors 255, 254, and 248. In shunt with the driving magnet 218 there is provided the relay 238 which remains energized during the period of energization of driving magnet 218 and upon its release a circuit is closed from ground, upper contact of sequence switch spring 240, left hand back contact of relay 238, conductor 241, right hand armature and back contact of relay 242, left hand back contact and armature of relay 243, conductor 244, winding of relay 245 to grounded battery 246, operating relay 245. The busy test is made in the usual manner. A ground is then applied by way of the right hand armature and back contact of relay 238, sequence switch spring 247 to the wiper 225, and to test terminal 248 for isolating the selected line. A circuit is also closed from ground, left hand armature and back contact of relay 207, sequence switch spring 240, left hand armature and back contact of relay 238, conductor 241, armature and back contact of relay 242, left hand back contact and armature of relay 243, conductor 244, winding of relay 245, to grounded battery 246, operating relay 245. A ringing circuit is then closed from the source 232, conductor 250, connecting board 237, conductor 251, lower right contact of sequence switch spring 252, conductor 253, winding of relay 242, left front contact of relay 245, wiper 224, conductor 254, the selective ringing apparatus of the called line, conductor 255, wiper 223, right armature and front contact of relay 245. Relay 242 is marginal and does not operate on the current flowing in this circuit. The ringer 236 is adjusted to operate on the current impressed by the source 232 on conductor 250, and the ringers at stations 233, 234, and 235, are adjusted to be inoperative upon this character of current; thus only a single station of the selected line is caused to be signalled. Upon removal by the wanted subscriber of his receiver from its hook a low resistance path through his transmitter circuit is closed in the well known manner, and the current is thereby increased sufficiently to cause the operation of marginal relay 242, which upon operating removes a short circuit from around relay 243. Relay 243 thereupon operates in turn and applies direct battery 256 to its own winding, and to the conductor 244. The grounded battery 256 is the same battery as grounded battery 246, and the winding of relay 245 is thus short circuited, and this relay is released. Ringing current is thus disconnected from the called line.

The operation of relay 243 closes also the following circuit, ground, right hand front contact of relay 243, upper right contact of sequence switch spring 212, power magnet of sequence switch 213, to grounded battery, and the sequence switch 213 is moved out of position 6 and since the upper right contact of sequence switch 212 continues closed in all positions up to and including 15, the sequence switch 213 is driven into position 16. A conversational circuit is now closed from the calling station 101 to the called station 257 as follows: Grounded battery 12, lower left winding of repeating coil 13, winding of relay 14, sequence switch contact 124, conductor 106, substation 101, interrupter contact 102, conductor 105, sequence switch contact 125, upper left winding of repeating coil 13 to ground. Inductively related to the left hand windings of repeating coil 13 are the right hand windings and a circuit is closed from grounded battery 12 through lower right winding of repeating coil 13, upper contact of sequence switch spring 196, wiper 180, conductor 203, upper contact of sequence switch spring 210, left hand back contact and armature of relay 245, wiper 224, conductor 254, the selective ringing apparatus of the called line, conductor 255, wiper 223, right armature and front contact of relay 245. Relay 242 is marginal and does not operate on the current flowing in this circuit. The ringer 236 is adjusted to operate on the current impressed by the source 232 on conductor 250, and the ringers at stations 233, 234, and 235, are adjusted to be inoperative upon this character of current; thus only a single station of the selected line is caused to be signalled. Upon removal by the wanted subscriber of his receiver from its hook a low resistance path through his transmitter circuit is closed in the well known manner, and the current is thereby increased sufficiently to cause the operation of marginal relay 242, which upon operating removes a short circuit from around relay 243. Relay 243 thereupon operates in turn and applies direct battery 256 to its own winding, and to the conductor 244. The grounded battery 256 is the same battery as grounded battery 246, and the winding of relay 245 is thus short circuited, and this relay is released. Ringing current is thus disconnected from the called line.

The operation of relay 243 closes also the following circuit, ground, right hand front contact of relay 243, upper right contact of sequence switch spring 212, power magnet of sequence switch 213, to grounded battery, and the sequence switch 213 is moved out of position 6 and since the upper right contact of sequence switch 212 continues closed in all positions up to and including 15, the sequence switch 213 is driven into position 16.

A conversational circuit is now closed from the calling station 101 to the called station 257 as follows: Grounded battery 12, lower left winding of repeating coil 13, winding of relay 14, sequence switch contact 124, conductor 106, substation 101, interrupter contact 102, conductor 105, sequence switch contact 125, upper left winding of repeating coil 13 to ground. Inductively related to the left hand windings of repeating coil 13 are the right hand windings and a circuit is closed from grounded battery 12 through lower right winding of repeating coil 13, upper contact of sequence switch spring 196, wiper 180, conductor 203, upper contact of sequence switch spring 210, left hand back contact and armature of relay 245, wiper 224, conductor 254, the selective ringing apparatus of the called line, conductor 255, wiper 223, right armature and front contact of relay 245. Relay 242 is marginal and does not operate on the current flowing in this circuit. The ringer 236 is adjusted to operate on the current impressed by the source 232 on conductor 250, and the ringers at stations 233, 234, and 235, are adjusted to be inoperative upon this character of current; thus only a single station of the selected line is caused to be signalled. Upon removal by the wanted subscriber of his receiver from its hook a low resistance path through his transmitter circuit is closed in the well known manner, and the current is thereby increased sufficiently to cause the operation of marginal relay 242, which upon operating removes a short circuit from around relay 243. Relay 243 thereupon operates in turn and applies direct battery 256 to its own winding, and to the conductor 244. The grounded battery 256 is the same battery as grounded battery 246, and the winding of relay 245 is thus short circuited, and this relay is released. Ringing current is thus disconnected from the called line.

- substation 257, conductor 255, wiper 223, right hand armature and back contact of relay 245, upper left contact of sequence switch spring 208, conductor 202, wiper 173, sequence switch spring 195, upper right winding of repeating coil 13 to ground. Upon the termination of conversation the subscribers replace the receivers on the switch hooks and the above described conversational circuit is broken. Relay 14 becomes deenergized and upon retracting its armature closes a circuit from ground, sequence switch spring 15, armature and back contact of relay 14, power magnet of sequence switch 131 to grounded battery, for moving this sequence switch out of position 16. Under control of its centering spring 188 sequence switch 131 moves into position 18. A circuit is then closed from grounded sequence switch spring 167, driving magnet 18 to grounded battery for energizing driving magnet 18, which upon attracting its armature presses the brush rod 176 against a constantly driven roller 20. Brush rod 176, wipers 178, 180 and 181, and brush 182, under control of the roller 20, are moved in a downward direction. When the brush 182 contacts with the conducting segment 16, a circuit is closed from the grounded brush 182, the conducting segment 16, conductor 17, upper right contact of sequence switch spring 170, power magnet of the sequence switch 131 to grounded battery, and the sequence switch 131 is moved out of position 18 and into position 1. The upper contact of sequence switch spring 167 opens the circuit of the driving magnet 18. The selector 116, and the sequence switch spring 131 are thus returned to normal for use on a subsequent call.
- When sequence switch 131 moves out of position 17, the circuit of winding of relay 205 is broken, and this relay upon retracting its armature closes a circuit from ground, armature and back contact of relay 205, upper left contact of sequence switch spring 212, power magnet of sequence switch 213 to grounded battery, for moving sequence switch 213 out of position 16 and into position 18. A circuit is now closed from ground, sequence switch spring 258, driving magnet 260 to grounded battery operating thereby the magnet 260, which upon attracting its armature forces the brush rod 221 into engagement with the down drive roller 261. The brush rod 221 and the wipers 223, 224, and 225, and the brush 214 are moved in a downward direction. When the brush 214 contacts with conducting segment 215 a circuit is closed from grounded brush 214, the conducting segment 215, lower contact of sequence switch spring 216, power magnet of sequence switch 213 to grounded battery for moving the sequence switch 213 out of position 18 and into position 1. Sequence switch contact 258, thereby opens the circuit of down drive magnet 260.
- By means of connecting board 237 the connections which exist in position 6 of the sequence switch 213 can be readily changed at will, and the character of ringing current applied to the called line in such position of the sequence switch or in any other position may be varied at will, thus the character of ringing current to be employed can be changed when desired without interfering with the numerical designation of the called station, or of any other station on the same line.
- Station 235 may be signalled in the following manner: The calling subscriber 101 operates the register magnet 138 in the usual manner and then causes the actuation of the register magnet 148 two times, thus bringing the wiper 152 into contact with conductor 2. Upon actuation of relay 207 and the movement of sequence switch 213, through positions $2\frac{1}{2}$ and $3\frac{1}{2}$, the number 2, 2', 1, 1', 0 and 0' relays are operated in the manner previously described, and the sequence switch 213 is brought to rest in position 4. The release of relay 207 thus closes a circuit by way of its left hand armature and back contact, sequence switch spring 240, left hand armature and back contact of relay 238, armature and back contact of relay 242, left hand armature and back contact of relay 243, conductor 244, winding of relay 245, grounded battery 246, for operating relay 245. Left hand front contact of this relay is now connected by way of the winding of relay 242, and the conductor 253 to conductor 262, and the source 232, impresses upon called line the character of current for which ringer 235 is adjusted to respond, and to which the ringers 233, 234 and 236 do not respond. The wipers 223, 224, and 225, have been driven to the same set of terminals as before the circuit of driving magnet 218, being closed by way of conducting segment 215, 228, 231, and 232, as before. Thus it will be seen that the one set of terminals is made use of for calling a plurality of stations on the same line, the auxilliary switch 213 being arranged to determine the character of ringing current which is to be impressed upon the selected set of terminals.
- In order that a clear understanding of the invention may be had, it should be borne in mind that the selector 220 is not positioned in direct response to the operation of the counting relays of the sender but hunts a position determined by the setting of sequence switch 213 which is variably positioned under the control of the sender. The sequence switch is of light construction, and is very rapid in operation. It can therefore be fully positioned before the selector 220 has advanced into engagement with the first

set of terminals. This makes possible a system in which the same setting of the final selector switch may be obtained under several conditions, even though the sequence switch 213 is not in the same position in each case. The manner in which this may be accomplished is as follows.

It will be assumed first that the sequence switch 213 has been brought to rest in position 3. In this case the selector switch will be brought into engagement with the seventh set of terminals, since its driving circuit will be successively completed by way of commutator segments 215, 228, 231, 15 291, 292, 293 and 232. However, when the selector reaches its seventh off normal position, its driving circuit is opened at the lower left hand contact of sequence switch spring 294 and the selector is brought to 20 rest. In this case, since the sequence switch 213 is standing in position 3, 60 cycle ringing current will be applied to the seventh set of terminals served by the selector switch.

In case sequence switch 213 is advanced in 25 position 4 under control of the sender, the selector 220 will again engage its seventh set of terminals, since its driving circuit will be successively completed until the seventh commutator segment is engaged, as is obvious from an inspection of the drawing. In this case, with the selector 220 in its seventh position, and sequence switch 213 in 30 position 4, 30 cycle ringing current will be applied to the line terminating in the seventh set of terminals served by the selector.

In case sequence switch 213 is advanced in position 9 under the control of the sender, the selector 220 will again be advanced 40 into engagement with its seventh set of terminals, since as before the driving circuit of magnet 218 is completed through the various sequence switch springs until commutator brush 214 engages segment 233. In 45 this case 45 cycle ringing current is applied to the line terminating in the seventh set of contacts by way of the lower left hand contact of sequence switch spring 295. If sequence switch 213 is advanced into position 6 under the control of the sender the selector switch 220 is again advanced into engagement with the terminals of the seventh line by means of circuits identical with those 55 previously described. In this case the called line is supplied with 16 cycle ringing current by way of the lower right hand contact of sequence switch spring 252.

From the foregoing it is obvious that the selector switch 220 is advanced into its seventh off normal position whenever sequence switch 213 is in any of the positions 3, 4, 6 or 9, and that ringing current of desired frequency is supplied in accordance with the particular setting of the sequence switch. 60 This allows of terminal per line working.

The cuttings of the sequence switch springs which control the movement of the selector switch have been disclosed so as to show only the method in which four stations can be signaled selectively on the seventh line. This has been done to render more easily understood the method of control. It is obvious that by properly arranging the open and closed positions of the control sequence switch springs that the principle of terminal per line ringing may be applied to all the lines served by the selector. 70

I claim as my invention:

1. In a telephone exchange system a series of registers, a control relay therefor, a calling substation adapted to intermittently operate said control relay, a second station connected in shunt with said first station and comprising a condenser, and means operative upon the actuation of said registers for discharging said condenser through the winding of said control relay. 80

2. In a telephone exchange comprising registers, a poly-station line, a condenser at each of the stations of said line, a calling device in series with a control relay, said control relay causing the actuation of said registers, and contacts operated by such registers for charging and discharging said condensers through the winding of said control relay. 90

3. In a telephone exchange system a plurality of registers for recording the designation of a wanted line or station, automatic switches controlled by said registers, a pulse circuit for said registers, and means controlled by said registers to reverse the current in said pulse circuit. 100

4. In a telephone exchange system, a step by step register switch, a pulse circuit for said register, and means controlled by said register to reverse the direction of current flow in said pulse circuit after each step of said register. 105

5. In a telephone exchange system, a plurality of step by step registers for recording the designation of a wanted line or station, a pulse circuit for said registers, and means controlled by said registers to reverse the direction of current flow in said pulse circuit after each step made by any one of said registers. 110

6. In a telephone exchange system, a plurality of called polystation lines, a source of variously characterized calling currents, means at each of the stations of said lines responsive to a single character of current, a switch operable by impulses for selecting a character of current and a selector controlled by said switch for selecting a line. 120

7. In a telephone exchange system, a plurality of polystation lines, a source of variously characterized ringing currents, means at each of the stations of said lines responsive to a single character of current, a switch 125

controlled by impulses for selecting a character of current and a selector locally controlled by said switch for seizing a designated line.

- 5 8. In a telephone exchange system, a plurality of stations connected to a single line, a source of variously characterized calling currents, means at each of said stations responsive to a single one of said currents, a
- 10 switch operable by impulses for selecting a

character of current, a selector controlled by said switch for selecting a line, and an interconnection between said switch and said selector such that a plurality of different settings of said switch result in a single setting 15 of said selector switch.

In testimony whereof, I hereunto set my hand.

GEORGE ALBEN E. LUNDELL.
